MINER'S ELECTRIC LAMP BULB

Albert George Gulliford, Conisborough, near
Rotherham, EnglandApplication February 23, 1937, Serial No. 127,152
In Great Britain March 3, 1936

1 Claim. (Cl. 176—30)

This invention relates to improvements in miner's electric lamp bulbs and has for its object to provide a fuse wire and fuse wire holder fitted to the bulb cap and connected to one of the bulb 5 filament wires such that in the event of the bulb becoming broken and the filament wires being forced together the fuse wire fuses inside the fuse holder and prevents any heating or sparking of the exposed filaments when current from a 10 miner's lamp battery passes through the lamp bulb.

Accordingly the present invention may be said to comprise a miner's lamp bulb having an insulated base inside the bulb cap to receive a 15 metal tube, screw, or socket or light which has in turn one of the filament leading-in wires of the bulb attached, and connected thereto one end cap of a cartridge fuse with fuse wire therein, the other end cap of the fuse forming one of the 20 contacts of the lamp bulb.

The invention will now be described more particularly, reference being taken to the accompanying drawing in which Figure 1 shows a sectional arrangement through the bulb with filaments and 25 fuse wire intact; Fig. 2 shows a sectional arrangement through the bulb as it would appear when the bulb globe is broken and filament wires pressed together and fused; Fig. 3 shows an elevation through a bulb similar to Fig. 1 but with 30 a bulb cap of screw type.

Figs. 1, 2, 3 each show an embodiment wherein the insulated base A is arranged in the bulb cap B. The base A is recessed at a_1 drilled out at a_2 and provided with a metal tube, screw, or socket 35 C. The screw or socket C is drilled through at c_1

to allow the filament leading-in wire f_1 to fit in. The globe E fitted with leading-in wires f_1 and f_2 is then placed in cap B with a section of leading-in wire f_1 fitting in tube, screw, or socket C and soldered or otherwise secured at c_2 . A section of filament leading-in wire f_2 is then soldered on cap B at b_1 . Globe E and base A with their fittings are then fixed in cap B by means of plaster, cement or like compound G. The cartridge fuse H comprises an insulated tube J fitted at each end with a metal cap K. A fuse wire L is provided in the insulated tube J and connected to each of the metal caps K, in the usual way. One end of the fuse holder H is then fitted in the underside of cap B coming flush up to the tube, screw, or socket C on base A thus forming a connection through fuse wire L to filament leading-in wire f_1 . The other end of fuse holder H projects below cap B for the purpose of forming a connection with a miner's lamp battery. The 5 fuse holder H with its fittings is then fixed in cap B and base A by means of plaster, cement or like compound G.

I claim:—

A lamp bulb for miner's electric lamps provided 25 with a fuse within the cap, characterized by a base plate of insulating material embedded in suitable cement within a metal lamp cap, a socket member fitted to said insulating plate and connected to one end of the filament, a fuse carried in said socket member and embedded in cement, the other end of such fuse protruding at the cap 30 surface to form due contact of the lamp bulb.

ALBERT GEORGE GULLIFORD. 35
